UNITED STATES PATENT OFFICE.

EDWIN E. BARNEY, OF NEW ROCHELLE, NEW YORK, ASSIGNOR TO REMINGTON TYPE-WRITER COMPANY, OF ILION, NEW YORK, A CORPORATION OF NEW YORK.

TYPEWRITING MACHINE.

1,425,825.

Specification of Letters Patent. Patented Aug. 15, 1922.

Application filed October 7, 1921. Serial No. 506,014.

To all whom it may concern:

Be it known that I, EDWIN E. BARNEY, citizen of the United States, and resident of New Rochelle, in the county of Westchester 5 and State of New York, have invented certain new and useful Improvements in Type-writing Machines, of which the following is a specification.

My invention relates to tabulator mechanism for typewriting and like machines.

The main object of the invention, generally stated, is to provide a simple comparatively inexpensive and effective tabulator mechanism which may be easily assembled 15 and readily incorporated in or detached from the machine; the ready detachment of the tabulator affording access to parts of the machine ordinarily covered or rendered difficult to gain access to by reason of the position of parts of the tabulator mechanism.

A further object of my invention is to so construct and connect parts of the tabulator mechanism that either a denominational selector or column selector may be readily 25 substituted, one for another, in the same machine without modifying, or without substantially modifying, the structural features of the machine itself.

To the above and other ends which will 30 hereinafter appear, my invention consists in the features of construction, arrangements of parts and combinations of devices set forth in the following description and particularly pointed out in the appended 35 claims.

In the accompanying drawings wherein like reference characters indicate corresponding parts in the different views,

Figure 1 is a fragmentary vertical fore- 40 and-aft sectional view of a typewriting machine equipped with the tabulator of my invention.

Figure 2 is a detail fragmentary sectional view, showing one end of a column stop bar 45 and the manner of adjustably connecting it to the carriage, the section being taken on the line 2—2 of Fig. 1 and looking in the direction of the arrow at said line.

Figure 3 is a like view of the same, the 50 section being taken on the line 3—3 of Fig. 2 and looking in the direction of the arrow at said line.

Figure 4 is an enlarged detail transverse 55 sectional view taken through the tabulator frame on the line 4—4 of Fig. 1 and looking in the direction of the arrow at said line.

Figure 5 is a detail perspective view of the tabulator frame and the parts carried thereby.

Figure 6 is a detail fragmentary trans- 60 verse sectional view of a portion of the construction, the section being taken on the line 6—6 of Fig. 7 and looking in the direction of the arrow at said line.

Figure 7 is a detail horizontal sectional 65 view with parts omitted, the section being taken on the line 7—7 of Fig. 1 and looking in the direction of the arrow at said line.

Figure 8 is a detail fragmentary front 70 view showing the guide plate detachably secured to the frame of the machine instead of to the tabulator frame as in the preceding figures.

Figure 9 is an enlarged detail fragmentary vertical sectional view of the same. 75

I have shown my invention, in the present instance, embodied in what is known as an improved Remington machine, although it should be understood that the invention is applicable and may be applied to other 80 styles of machines. I have only shown so much of a typewriting machine as may be necessary to arrive at an understanding of the invention in its embodiment therein. It should be understood, however, that so far 85 as the typewriting machine is concerned, the parts may be presumed, for the purpose of illustrating my invention, to be the same as those ordinarily employed in the improved Remington machine. 90

The frame of the machine comprises a base 1, corner posts 2 and a top plate 3. A carriage 4 is supported to travel over the top plate from side to side of the machine on fixed guide rails, the rear fixed guide rail 95 being indicated at 5. A feed rack 6 is carried by arms 7, pivoted at 8 to the carriage. The feed rack meshes with a feed pinion 9, controlled by an escapement wheel 10 and the usual escapement dogs (not shown), to 100 control the step-by-step letter feed movement of the carriage.

Fixed to and projecting rearwardly from the carriage near each end thereof is a supporting or bracket arm 11. Each arm is formed with a stop rod supporting portion 12 having a slot 13 to receive the stem of a headed screw 14 threaded into a tapped opening in a stop rod 15. From an inspection of Fig. 3 it will be understood that the 105 length and width of each slot 13 is considerably larger than the diameter of the stem 110

of the screw received therein, in order to enable a fore-and-aft as well as a longitudinal adjustment of the stop rod on the arms 11 to be effected. This provides for properly 5 adjusting the stop bar with the stops thereon relatively to the key actuated stops, both fore-and-aft of the machine and in the direction of the travel of the carriage, and therefore there is no necessity of adjusting 10 the key controlled stops or the tabulator frame which carries them. It will be seen that the head of each screw 14 overlaps the slot 13 in the companion arm, and is effective to clamp the bar 15 in adjusted position 15 on its supporting arm. In order, however, to more firmly secure the rod against displacement during the impact of the stops and arrest of the carriage, I have provided one or both of the arms 11 with an upturned 20 end 16. Each end 16 is tapped to receive a set screw 17 which bears at its inner end against an end of the stop rod 15, and positively prevents a longitudinal displacement of the rod on the arms in one direction. The 25 right-hand bracket arm 11 is the one where the set screw 17 is most useful, but both arms may be provided with such a set screw if desired.

The stop rod 15 may carry column stops 30 18 of any suitable construction. In the present instance the stops are shown mounted for rearward movement into operative position in interdental spaces 19 at letter space intervals in the toothed portion of the bar 35 15, and under control of a key actuated stop-setting member (not shown), as is common in Remington machines long in use on the market. A wiper or cam is usually employed to move the stops forwardly into 40 inoperative position on the stop bar.

The rear side of the top plate is recessed to receive, with a snug fit, an upstanding tabulator frame 20, the side walls of the recess and depending lugs 21 on the top 45 plate which are aligned with said walls firmly supporting the tabulator frame against lateral movement as in the construction disclosed in the patent to G. A. Seib, No. 1,273,545, dated July 23, 1918. The 50 upper portion of the tabulator frame 20 is connected to the frame of the machine by screws 22 which pass freely through openings in the lugs 21 on the top plate, and are threaded into tapped openings in the body 55 of the tabulator frame, as best shown in Fig. 4. These screws extend in beyond the sides of the tabulator frame and are received in tapped openings in a fulcrum member 23, to secure the latter in place in 60 the frame 20. The lower end of the tabulator frame, near each side thereof, has an opening which extends therethrough fore-and-aft of the machine, as best shown in Fig. 7; the forward portion of this opening being tapped to receive an externally

threaded boss 24. The forward end of each boss extends beyond the front edge of the lower portion of the tabulator frame and constitutes a contact that bears against the base 1 of the machine. These adjustable 70 bosses are provided in order to take care of any irregularity of manufacture, and enable a proper contact between the tabulator frame and the base of the machine to be effected irrespective of any such irregularities of manufacture, and without straining the casting of the tabulator frame when the latter is secured to the base of the machine. A headed screw 25 extends through the smooth bore of each boss and has its 75 forward end threaded into a tapped opening in the base, thus firmly, though detachably, securing the tabulator frame at its 80 lower end to the base of the machine.

The fulcrum member 23 hereinbefore referred to, is circular in cross section and has parallel peripheral grooves 26 formed therein throughout its length. The bottom wall 27 of each groove is formed as a cylindrical surface, and constitutes a fulcrum 90 for an upright actuating member or lever 28, whereas the circular plate-like partitions 29 of the fulcrum member maintain the levers 28 properly spaced apart at the fulcrum and guide them in their movements. 95 The rear edge of each lever 28 is formed with a semi-circular bearing recess 30, where it is seated and fulcrums on the bottom wall 27 of its slot 26. Associated with each lever 28 is a wire returning spring 31, 100 bearing near one end against a pin 32 carried by and projecting laterally from the companion lever 28. Each spring 31 bears intermediate its ends against the periphery of one of the partitions 29. The lower end 105 portion of each spring passes between two adjacent levers 28 and is hooked, looped or bent at its lower end, as at 33, around a rod 34 secured to the tabulator frame and forming an anchorage for the lower ends of 110 all of the springs. As shown in dotted lines in Fig. 4, the rod 34 is in the nature of a screw which passes freely through an opening in one side of the frame 20 and has its threaded end received in a tapped opening 115 in the other side of the frame. The force of each spring 31 is exerted not only to move the upper end of its lever rearwardly, and thus return the lever to normal position, but also to maintain the lever seated on 120 its fulcrum.

In the present instance the stops 35, which are projected into the path of the operative column stops 18 and which are actuated by the levers 28, are formed as forwardly extending projections on said levers, although for the purpose of my present invention it is immaterial how the stops which are actuated by the levers 28 are constructed and mounted. In the present instance the 130

stops 35 extend through a guide comb comprising two independent sections 36, secured to the upper front face of the tabulator frame by screws 37. Each section of the comb is provided with teeth 38 between which the stops 35 are received and guided. The lower portion of the tabulator frame is formed with a web 39 extending transversely across it. This web is slotted fore-and-aft of the machine at 40, to form a guide comb in which the parallel lower end portions of the levers 28 are received, and by which they are guided. The lower end of each lever 28 terminates a short distance below the guide comb and is provided at its front edge with a contact portion 41, which preferably is slightly rounded, as indicated in Fig. 1.

As the construction is illustrated in Figs. 1-7 inclusive, forwardly projecting lugs 42 extend from the lower end of the tabulator frame through a cutout or opening 43 in the base 1 of the machine, and these lugs are tapped in their forward ends to receive headed screws 44. The stems of these screws pass through holes in a sheet metal guide plate 45 to firmly, though detachably, connect the guide plate to the tabulator frame. The upper and lower edges of the guide plate are formed with a series of oppositely disposed semi-circular recesses, notches or guide openings 46; a recess 46 of the upper series being directly above a recess of the lower series, as shown in Fig. 6. A series of push rods or key controlled actuating members 47 extend fore-and-aft of the machine, the rods being arranged in substantial parallelism at their rear end portions 47^a though flaring outwardly at their forward ends. The rear end of each rod is looped or bent back over the body portion thereof to provide a forwardly projecting arm 48. This arm extends above and parallel with the rear part 47^a of the rod just below the arm, and is connected thereto by an upstanding portion 49 that preferably is flattened to provide a rear contact face 50, as best shown in Fig. 7. It may be said, therefore, that the parts 47^a and 48 on each rod constitute parallel arms, and they will be so referred to herein. A distance between the arms 47^a and 48 of each rod accords substantially to the distance between a guide recess 46 in the bottom edge of the plate 45 and the corresponding recess in the upper edge of the plate. When, therefore, the guide 45 is in place in the looped ends of the rods, each upper recess 46 in the guide receives an arm 48, and the corresponding lower recess receives the arm 47^a of the same rod. The rear ends of the rods with their arms are thus supported and guided in their fore-and-aft movements, and are prevented from turning in the guide. This manner of mounting and guiding the

push rods at their rear ends provides a simple and inexpensive means for assuring a proper registration of the contact 50 on each push rod with the contact 41 on the associate stop actuating lever 28, as will be understood from an inspection of Fig. 7, without requiring each push rod to be connected to its associate lever, thus facilitating an assembling and a detaching of the parts of the structure when desired. It will be observed, moreover, that the guide comb 39-40 coacts with the levers 28 adjacent to the contacts 41 thereon, whereas the guide 45 coacts with the rods adjacent to the contacts 50 thereon, so that the levers and rods are effectively guided near the points where they coact, and there is no opportunity for a relative lateral displacement of the members at these points to throw them out of register.

The push rods may be actuated in any suitable manner, and may be supported at their forward ends by any suitable means. In the present instance each rod extends through a guide opening in an auxiliary guide or frame 51, detachably secured to the base of the machine by screws 52 that are received at their threaded ends in tapped openings in the base of the machine. Each push rod 47 is shown in the present instance provided with a key 53 on its front end, and by which the rod and the parts controlled thereby may be actuated.

I prefer in practice to provide a felt pad 54 on the rear face of the guide 45 and with which the member 49 of each rod may coact in the return movement of the rod, to reduce or prevent noise that might be brought about by the members 49 striking the guide in their return movements.

In order to effect a release of the carriage at each actuation of the tabulator key, I have provided a universal release bar 55 which may be formed as one side of a sheet metal frame, designated as a whole by the reference numeral 57. The universal bar 55 is preferably bent at right angles to the plane of the remainder of the frame 57, as best shown in Fig. 1. This presents a side face of the universal bar for co-operation with the rounded contacts 58 on the levers 28. Parallel side bars 59 of the frame 57 extend through guide grooves or notches 60 in the guide plate 45, thus providing means for supporting and guiding the frame 57 in its fore-and-aft sliding movements. Projecting outwardly from the side bars 59 are two arms 61, each terminating in a reduced portion 62 which constitutes a pivot by which the frame 57 is connected to the remainder of the carriage releasing devices. The pivots are seated in openings 63 in two depending sheet metal arms 64 and 65, each fixedly secured to a rock shaft 66, the ends of which are received in bearing openings 67 in arms of a sheet metal bracket 68. The

latter is secured by screws 69 and bolts 70 to the base of the machine. I prefer to make the arms 64 and 65 slightly resilient laterally, so that they may be sprung away from each other to facilitate the introduction of the pivots 62 of the frame 57 in the openings 63 in assembling the parts, or to afford a removal of the pivots to detach the parts when desired. The arms 64 of the 10 rocking releasing member has a forwardly projecting arm 71, pivoted at 72 to an upwardly extending sheet metal link 73. This link extends through an opening 74 in the top plate, and has its upper end pivoted at 15 75 to a rocking frame or member 76. The latter is pivoted at 77 to a sheet metal bracket 78 secured to the top plate of the machine. The swinging member 76 carries the usual releasing and retarding device employed in Remington machines and comprising a pinion 79 operatively connected to a retarding drum 80.

Each actuation of a tabulator key 53 causes the lower end of the associate lever 28 to move rearwardly, and at the last portion of its movement to take up the universal release bar 55, moving the bar and its frame rearwardly, and through the intermediate connections, swinging the frame or carrier 30 76 so that its forward end moves upwardly. This is effective to throw the pinion 79 into mesh with the feed rack 6 and lift the latter to disconnect it from the feed pinion 79, at the same time operatively connecting the retarding device to the carriage. 35

The parts are returned from their actuated positions by the spring 31 of the actuated lever 28, and by a contractile returning spring 81 connected at one end, as at 40 82, to the frame 57, and at its opposite end to an arm 83 of a sheet metal bracket. This bracket is provided with a second arm 84 which acts as a stop to limit the return movement of the frame 57. The 45 bracket 83-84 is connected to a plate 85 supported in place by arms 85^a secured to the base by the screws 69 and bolts 70 which hold the bracket 68 in place, and also secure the fulcrum plate 86 for the key levers 50 87 to the base. If desired the plate 85, where it extends beneath the key levers 87, may be sheathed with a felt pad.

When key set column stops 18, as herein shown, are employed, it is desirable to form 55 as a part of the casting of the tabulator frame 20 supporting means for a cam wiper 88, which cam is controlled in its movements into and out of operative position in the usual manner by a finger key 89, indicated in Fig. 5.

It will be seen that each lever 28 is guided at three points in the length thereof, i.e. at its upper end by the comb plates 36, on its fulcrum by the partition members 29, and 60 at its lower end by the comb 39-40.

In the construction disclosed in Figs. 8 and 9, the parts are the same as those previously described, except that the guide plate 45^a is slightly modified to provide outwardly projecting ears 90 apertured to 70 receive headed screws 44^a that are received in tapped openings in faced lugs 91 on the base of the machine. In this construction therefore the guide plate 45^a is connected directly to the frame of the machine 75 instead of to the tabulator frame, as in the previously described construction. By reason of this modified form of construction the tabulator frame with the parts carried thereby may be removed independently of the guide plate 45^a and the parts which are supported and guided thereby, as will hereinafter more clearly appear. 80

It is sometimes necessary to gain access to parts of the machine which are ordinarily covered, or difficult to gain access to by reason of the position of parts of the tabulator. In this connection it may be pointed out that the upstanding tabulator frame 20, as is usually the case, is secured in position directly back of the escapement mechanism and prevents ready access thereto. Should it become necessary to remove the tabulator frame 20 from the position it normally occupies, this may be accomplished by removing the screws 22 and 25 and tilting the upper end of the tabulator frame rearwardly a limited distance; the manner of supporting the rods 47 by a comb plate 45 not interfering with such 95 movement of the tabulator frame. 100

If, however, it is necessary or desirable to wholly detach the tabulator from the machine, this may be accomplished by removing in addition the screws 52 which connect the guide or frame 51 to the machine. One of the arms 64-65 may then be flexed laterally to displace a pivot 62 from the bearing opening therein, after which the forward end of the frame 57 may receive 110 a slight lateral displacement to withdraw the other pivot 62 from its bearing. The entire tabulator comprising the frame 20, the stops 35, the levers 28, the carriage releasing frame 57, the push rods 47, the 115 guide plate 45, and the guide 51 may then be removed as a single unit from the machine.

There are certain advantages attained by mounting the guide plate 45^a independently 120 of the tabulator frame directly on the frame of the machine, as shown in Figs. 8 and 9. Thus with this construction should it become necessary to detach the tabulator frame 20 to give access to the escapement, 125 or for any other purpose, it is merely necessary to remove the screws 22 and 25, when the tabulator frame with the levers 28 may be lifted and detached from the machine, leaving the guide plate 45^a, the universal 130

release frame 57, push rods 47, and guide 51 in the machine, with the release frame connected to the parts which effect a release of the carriage. In returning the tabulator frame 20 it is lowered into position with the lower ends of the levers 28 properly inserted between the ends of the push rods and the universal release bar 55. The screws 22 and 25 are then threaded into place to secure the tabulator frame to the machine with the parts in proper co-operative relation. This enables the tabulator frame to be readily detached from the machine, together with the parts carried thereby, without any preliminary detachment between the parts of the tabulator mechanism and the means by which the carriage releasing devices are actuated. In a like manner the tabulator frame may be reintroduced into the machine without connecting any of the parts of the tabulator or the means by which the carriage releasing devices are actuated.

In the present instance I have disclosed my invention in its embodiment in a denominational tabulator, but it is immaterial whether the invention be incorporated in a denominational selector or a column selector. Thus, for example, so far as my invention is concerned it is immaterial whether the push rods, constructed and mounted at their rear ends like the push rods 47, coact with the actuating levers, similar to the levers 28, be employed to project denominational stops as herein shown, or to project column selecting stops as in the patent to G. A. Seib hereinbefore referred to. It is to be understood that in either instance the tabulator frame is constructed in substantially the same manner; is connected to the frame of the machine in the same manner; that in both instances the stops and levers which actuate them are detachable with the tabulator frame; that in both instances the carriage release bar or frame is or may be constructed, mounted and operated in the same manner; that in both instances the tabulator frame with the stops and actuating levers may be detached from the machine independently of the other parts of the tabulator when the guide plate 45^a is independently supported on the frame of the machine, as indicated in Figs. 8 and 9; that the essential parts of the present invention in both cases remain the same and are combined and coact in the same manner, and that the construction is such that one character of tabulator may be readily substituted for another without materially changing any of the structural features of the typewriting machine. It will be seen moreover that in both instances the construction is such that the parts of the tabulator do not occupy any space within the main body of the machine, passing be-

neath and up in the rear of the working parts of the machine, and leaving the space within the main body of the machine free from interference or obstruction by the tabulator to mount various parts of the type-writing machine proper.

From the foregoing description it will be understood that by my invention I have provided a comparatively simple and inexpensive construction in which the parts may be readily assembled and incorporated in the machine and may be readily detached when desired.

What I claim as new and desire to secure by Letters Patent, is:

1. In a tabulator, the combination of a series of horizontally arranged key controlled actuating members each formed with two parallel arms and an upstanding contacting portion, and a series of stop actuating levers registering with said upstanding contacting portions and adapted to be moved thereby.

2. In a tabulator, the combination of a series of key controlled actuating rods each looped at one end to form two parallel arms, a series of stop actuating levers registering with the looped portions of the actuating rods and adapted to be moved thereby, and a guide plate arranged between said arms and notched at its edges to receive and guide said arms.

3. In a tabulator, the combination of a series of key controlled actuating rods each looped at one end to form two parallel arms, and having its looped portion flattened to form a contact face, a guide which receives and guides the parallel arms of each of said rods, and a stop controlling member coacting with the contact face of each rod.

4. In a tabulator, the combination of a series of key controlled actuating rods each looped at one end to form two parallel arms, and having its looped portion flattened to form a contact face, a guide plate received between said parallel arms and notched in opposite edges to receive and guide said arms, and stop controlling members disconnected from but aligned and coacting with said flattened contact faces on the rods.

5. In a tabulator, the combination of a series of key controlled actuating members each formed with two parallel arms, a guide for said members provided with guide openings in which said parallel arms are received and guided, and a carriage release device mounted to slide on and be guided by said guide.

6. A tabulator comprising a series of stops, key actuated push rods each formed with a looped end that provides parallel arms, and a guide having apertures in which said arms are received to support

and guide the push rods and prevent them from turning.

7. A tabulator comprising a series of stops, key actuated push rods each bent at 5 one end to form parallel arms and an intermediate contact portion, and a guide received between the parallel arms of said rods and recessed at opposite edges to receive support and guide said arms and prevent the rods from turning.

8. In a tabulator for typewriting and like machines, the combination of a detachable tabulator frame, a series of stops and stop actuating members carried by and detachable with said frame, a series of key controlled actuating members detached from but co-operative with said stop actuating members and each formed with two parallel arms, and a guide with recesses in 20 which said parallel arms are received and guided.

9. In a tabulator comprising a series of stops, key actuated push rods each bent at one end to form parallel arms and an intermediate contact portion, a guide received between the parallel arms of said rods and recessed at opposite edges to receive support and guide said arms and prevent the rods from turning, a detachable tabulator frame, stops, and stop actuating members detachable with said frame, each of said stop actuating members being maintained aligned with the contact portion of the associated push rod when the tabulator frame 35 is secured in place.

10. A tabulator comprising a series of stops, key actuated push rods each formed with a looped end that provides parallel arms, a guide having apertures in which 40 said arms are received to support and guide the push rods and prevent them from turning, a detachable tabulator frame, a series of stop actuating devices detachable with said frame and which when said frame is in place are maintained aligned with the looped ends of said push rods and each with the looped end of its associated push rod, and means for supporting said guide on the frame of the machine independently of said 45 detachable frame, whereby the guide may support and maintain the push rods properly positioned in place in the machine when the tabulator frame is detached independently thereof.

55. 11. In a tabulator, the combination of a series of key controlled actuating rods each looped at one end to form two parallel arms and having its looped portion flattened to form a contact face, a guide which receives 60 and guides the parallel arms of each of said rods, a stop controlling member coacting with the contact face of each rod, and a detachable tabulator frame carrying said stop controlling members and with which the 65 latter are detachable from the machine.

12. In a tabulator, the combination of a series of key controlled actuating rods each looped at one end to form two parallel arms and having its looped portion flattened to form a contact face, a guide which receives 70 and guides the parallel arms of each of said rods, a stop controlling member coacting with the contact face of each rod, and a carriage release bar mounted for sliding movement on said guide and with which said stop 75 controlling members coact.

13. In a tabulator, the combination of a series of key controlled actuating rods each looped at one end to form two parallel arms and having its looped portion flattened to 80 form a contact face, a guide which receives and guides the parallel arms of each of said rods, a stop controlling member coacting with the contact face of each rod, a carriage release bar mounted for sliding movement on 85 said guide and with which said stop controlling members coact, and a detachable tabulator frame in which said stop controlling members are mounted for detachment there- 90 with.

14. In a tabulator, the combination of a series of key controlled actuating rods each looped at one end to form two parallel arms and having its looped portion flattened to form a contact face, a guide which receives 95 and guides the parallel arms of each of said rods, a stop controlling member coacting with the contact face of each rod, a carriage release bar mounted for sliding movement on said guide and with which 100 said stop controlling members coact, a detachable tabulator frame in which said stop controlling members are mounted for detachment therewith, and means for detachably connecting said guide to the frame of 105 the machine independently of said tabulator frame, whereby the tabulator frame with the stop controlling member may be detached from the machine independently of said guide and while the latter supports 110 said actuating rods and carriage release bar in the machine.

15. In a typewriting or like machine, the combination of upstand stop actuating levers, an upstanding tabulator frame arranged at the rear of the machine and in which said levers are pivoted, means for detachably connecting said tabulator frame to the frame of the machine, a series of key actuated push rods that extend fore-and-aft 120 of the machine and each of which is bent at its rear end and formed as a contact to coact with the forward edges of the associated stop actuating lever at the lower end portion thereof, and means for guiding said levers and push rods and maintaining them in 125 register.

16. In a typewriting or like machine, the combination of upstand stop actuating levers, an upstanding tabulator frame ar- 130

ranged at the rear of the machine and in which said levers are pivoted, means for detachably connecting said tabulator frame to the frame of the machine, a series of key actuated push rods that extend fore-and-aft of the machine and each of which is bent at its rear end and formed as a contact to coact with the forward edges of the associated stop actuating lever at the lower end portion thereof, the bending of each push rod also providing an arm arranged in parallelism with the body of the rod, and a guide having openings in which the parallel parts of each push rod are seated and guided to support each rod and prevent it from turning.

17. In a typewriting or like machine, the combination of upstand stop actuating levers, an upstanding tabulator frame arranged at the rear of the machine and in which said levers are pivoted, means for detachably connecting said tabulator frame to the frame of the machine, a series of key actuated push rods that extend fore-and-aft of the machine and each of which is bent at its rear end and formed as a contact to coact with the forward edges of the associated stop actuating lever at the lower end portion thereof, the bending of each push rod also providing an arm arranged in parallelism with the body of the rod, a guide comb at the lower end portion of the tabulator frame for said levers, a guide plate having guide recesses in opposite edges thereof and in which recesses the parallel portions of the push rods are seated and adapted to slide.

18. In a typewriting or like machine, the combination of upstand stop actuating levers, an upstanding tabulator frame arranged at the rear of the machine and in which said levers are pivoted, means for detachably connecting said tabulator frame to the frame of the machine, a series of key actuated push rods that extend fore-and-aft of the machine and each of which is bent at its rear end and formed as a contact to coact with the forward edges of the associated stop actuating lever at the lower end portion thereof, the bending of each push rod also providing an arm arranged in parallelism with the body of the rod, a guide comb at the lower end portion of the tabulator frame for said levers, a guide plate having guide recesses in opposite edges thereof and in which recesses the parallel portions of the push rods are seated and adapted to slide, and a carriage release member supported and guided by said guide plate and with which the lower end portion of the stop actuating levers coact.

19. In a typewriting or like machine, the combination of upstand stop actuating levers, an upstanding tabulator frame ar-

ranged at the rear of the machine and in which said levers are pivoted, means for detachably connecting said tabulator frame to the frame of the machine, a series of key actuated push rods that extend fore-and-aft of the machine and each of which is bent at its rear end and formed as a contact to coact with the forward edges of the associated stop actuating lever at the lower end portion thereof, the bending of each push rod also providing an arm arranged in parallelism with the body of the rod, a guide comb at the lower end portion of the tabulator frame for said levers, a guide plate having guide recesses in opposite edges thereof and in which recesses the parallel portions of the push rods are seated and adapted to slide, a carriage release member supported and guided by said guide plate and with which the lower end portion of the stop actuating levers coact, and means for connecting said guide plate to the frame of the machine independently of said tabulator frame, whereby the tabulator frame with the stop actuating levers may be detached from the machine independently of said stop rods and carriage release member and while the same are maintained properly positioned in the machine.

20. In a tabulator, the combination of a series of actuating levers, and carriage releasing means comprising a rectangular frame mounted to slide in substantially a horizontal plane and through which said levers extend at substantially right angles to its plane of movement, one side of said frame constituting a universal bar with which the levers coact to slide the frame.

21. In a tabulator, the combination of a series of actuating levers; a tabulator frame which carries said levers; carriage releasing means comprising a rectangular frame through which said levers extend and one side of which constitutes a universal bar with which the levers coact to actuate the frame; means on the frame of the machine for supporting and guiding said frame; and means for detachably connecting the tabulator frame to the frame of the machine, whereby the tabulator frame with the levers carried thereby may be detached from the frame of the machine independently of said rectangular frame and while the latter remains in place in the machine.

22. In a tabulator, the combination of a series of actuating levers; carriage releasing means comprising a rectangular frame through which said levers extend and one side of which constitutes a universal bar with which the levers coact to operate the frame; a guide member by which said rectangular frame is supported and guided; and a series of key controlled rods supported and guided by said guide members and cooperative with said levers to actuate them.

23. In a tabulator, the combination of a series of actuating levers; a tabulator frame which carries said levers; carriage releasing means comprising a rectangular frame 5 through which said levers extend and one side of which constitutes a universal bar with which the levers coact to actuate the frame; a guide member secured to the frame of the machine and by which said rectangular frame is supported and guided; a series 10 of key controlled rods supported and guided by said guide member and detached from but co-operative with said levers to actuate them; and means for detachably connecting

the tabulator frame to the frame of the 15 machine, whereby the tabulator frame with the levers carried thereby may be detached from the machine independently of said rectangular frame, guide member and key controlled rods.

20

Signed at the borough of Manhattan, city of New York, in the county of New York, and State of New York, this 6th day of October, A. D. 1921.
